CAN OPENER COMBINED WITH A STOPPER
AND A DISPENSING DEVICE

Jean Marie Joseph Plasse, El Hajeb, Morocco

Application March 3, 1938, Serial No. 193,716
In France April 23, 1937

1 Claim. (Cl. 221—23)

My invention relates to a can opener combined with a stopper and a dispensing device; it permits of opening any ordinary can of the trade, of converting it instantly in a hermetically sealed dispensing can provided with a stopper.

The drawing represents, by way of example, an embodiment of my invention; in the various figures, like reference characters indicate corresponding parts.

Fig. 1 is a perspective view of the complete device which consists of an opener, a fixing washer, a nut and a closing cap. Figure 2 is a horizontal section through the opener; Figure 3 is a plan view of the fixing washer; Figures 4 and 5 are plan views on the top of the can, which is partly torn away. The opener consists of a screw-threaded tube *a* fixed on a basis *b* of hardened steel plate which projects a number of depending teeth *q*, *r*, *s*, *t* provided with sharpened oblique cutting edges and ending in a sharp point. The tube *a* has a longitudinal groove *c* cutting its screw thread. The washer *f* has an inwardly projected tooth *h* adapted to slide in groove *c* when washer *f* is engaged over tube *a*. A nut *e* and a cap *d* are adapted to be screwed on tube *a*. The device is used as follows. The points *q*, *r*, *s*, *t* are placed on the top of a can near the edge, in order that the projection *g* of washer *f* cannot make a complete revolution round tube *a*, its end contacting with the protruding edge *xy* of the top of the can, as shown by Figure 5. A blow on the cap *d* drives the points *q*, *r*, *s*, *t* through the top of the can, the sharp edges of the teeth cutting gradually the metal till a piece correspond-

the teeth enter the can. Now, tube *a* is turned about 45° on its axis; washer *f* is lowered till it rests on the top of the can and afterwards turned till the end of its projection abuts the rim *XY*; screw *e* is screwed down to press upon washer *f*, thus sealing the can. Tube *a* can now serve as a pouring spout; after use, it can be stoppered by screwing on cap *d*.

An elastic joint may be placed under washer *f* to ensure better closure. The number of cutting teeth is facultative. Tube *a* may be secured against rotation in any other way. The cutting teeth may be inclined outwards in order to facilitate the extraction of part *b* out of the can. Nut *e* may be knurled, winged or pinned. When tube *a* is provided with a laterally projecting spout which permits of holding the device against rotation, washer *f* and slot *c* may be dispensed with, the nut *e* being then made large enough to cover the hole in the can. When the can has been emptied the device may be withdrawn to be used on another can.

Having now described my said invention and ascertained the manner in which it is to be performed, I declare that what I claim is:

In a can opener, the combination of a screw-threaded tube fixed upon a base provided with a number of depending teeth having sharp points and cutting edges, said tube having a longitudinal groove from end to end, a washer with an inner tooth adapted to slide in said groove after the washer has been slipped over said tube, a nut and a cap adapted to be screwed on said tube, substantially as described.

JEAN MARIE JOSEPH PLASSE. 35
